RUSSELL F. JOHNSON, OF ROBERTS, CALIFORNIA.

PISTON.

1,245,236.

Specification of Letters Patent.

Patented Nov. 6, 1917.

Application filed July 6, 1916. Serial No. 107,784.

To all whom it may concern:

Be it known that I, RUSSELL F. JOHNSON, a citizen of the United States, residing at Roberts, in the county of Los Angeles and 5 State of California, have invented new and useful Improvements in Pistons, of which the following is a specification.

This invention relates to a reciprocating piston and particularly pertains to a piston 10 adapted to be used within high duty pumps and compressors, as well as engines of various types.

It is an object of this invention to provide a piston for use in the above classes of machinery which has a cylinder intake valve incorporated in its construction, said valve being adapted to open upon the back stroke of the piston and to tightly close upon the compression stroke without the aid of 20 springs or complicated operating mechanism.

Another object is to provide a piston which is adapted to have a floating action as well as be free to rotate independent of 25 the piston rod and will thus properly adjust itself to the surface of its cylinder without binding and without uneven wear.

Another object is to provide baffle members through which the incoming fluid, 30 passes and which members will act to prevent foreign substance from passing into the cylinder and thus creating damage therein.

Another object is to provide simple means 35 for regulating and limiting the movement of the valve and at the same time insuring that the valve will be open the full length of the back stroke and closed the full length of the compression stroke.

Another object is to provide a combined piston and valve which is adapted to close in a more positive manner the higher the 40 compression is within the cylinder.

It is a further object to provide a combined piston and cylinder valve which is possessed of few moving parts and which eliminates the use of intricate cylinder 45 valve mechanisms.

Other objects will appear hereinafter.

The invention is illustrated in the accompanying drawings in which:

Figure 1 is a view in vertical section illustrating the piston as at the end of its compression stroke and further illustrating in

dotted lines the relative position of the valve 55 and piston members at the beginning of the back stroke.

Fig. 2 is a view in section as seen on the line 2—2 of Fig. 1 and illustrates the baffle plate and the arrangement of the orifices 60 therethrough.

Referring to the drawings more particularly, 10 indicates a pump cylinder which may be of any preferred type and which is here shown as being provided with a check-valve 11. The valve construction here shown, however, is not imperative and is shown merely for the sake of clearness. Mounted to reciprocate within the cylinder, is a piston 12 which is fitted with a suitable 65 number of piston rings 13 around its outer periphery. The piston is actuated by a piston rod 14 upon the end of which is a puppet valve mechanism 15 adapted to act in coöperation with the piston and within 75 which the present invention is involved.

The puppet valve 15 is tapered from its interior face and is adapted to seat upon a taper valve seat 16 formed concentric with and through the end wall 17 of the piston. 80 Formed upon the piston rod 14 and in the rear of the valve member 15 is a pair of circular baffle and supporting disks 18 and 19 which are of an outside diameter approximately equal to the inside diameter of 85 the piston and are adapted to bear thereagainst and reciprocate thereupon. These baffle disks are confined within the piston by means of a locking ring 20 which is externally threaded and engages an internally 90 threaded bore 21 formed at the rear end of the piston. A locking pin 22 is driven through the piston wall and into the locking ring to hold it in position. It will thus be seen that by adjusting the ring member 20 95 various spaces may be made between the inner face of the ring and the rear face of the disk for a purpose which will be hereafter described. The disks 18 and 19 are each provided with a series of perforations 23 100 which are concentrically arranged around the disks and the piston rod. These perforations are provided for the purpose of allowing a fluid to pass from the rear of the piston around the open valve and into the 105 cylinder head upon the back stroke of the piston.

In operation, the piston rod 14 is recipro-

cated by means of any preferred operating mechanism and, when so actuated, moves the baffle disks 18 and 19 and the puppet valve head 15 simultaneously. While making its compression stroke, as indicated by the arrow —a—, the end of the piston rod is forced through the piston having its bearing upon the disk members as they in turn slide along the inside of the piston. 10 Upon the initial movement of the piston rod on its compression stroke, the piston lags behind due to the surface area of the end 17 of the piston which is opposed by the compression within the cylinder. This allows the valve 15 to become positively seated upon the valve seat 16 after which the rod and piston will move in unison throughout the compression stroke. Upon the return stroke, the piston rod will draw away from 20 the piston and allow the valve to become unseated from the seat 16. The amount of opening between the valve member and its seat will be determined by the adjustment of the adjusting ring 20 which is engaged 25 by the disk 19 upon the return stroke and thus limits the opening of the valve as well as provides a substantial member by which the piston may be returned to the end of its draw stroke. It is evident that while the 30 piston is returning throughout its draw stroke air or a fluid may pass through the perforations 23 and around the valve into the cylinder.

It will thus be seen that a combined piston and cylinder valve is here provided which eliminates the use of complicated valve mechanism and which will operate in a simple and effective manner without great danger of becoming disordered or worn.

I claim:

1. A piston, comprising a cylindrical piston body member, an end wall across one end thereof, a conical valve seat formed through said end wall, and with its enlarged diameter within the piston member, 45 an adjusting ring mounted at the opposite or open end of the piston member, a piston rod adapted to extend through a central opening in the adjustment ring and into the piston body, a pair of spaced baffle disks 60 formed upon the piston rod and adapted to support it within the body member, said disks restricted in their movement by the adjusting ring, and a valve member formed at the terminating end of the piston rod and 55 adapted to seat upon the conical seat in the end wall of the body member, and means whereby the reciprocation of the piston rod will act to open and close the valve as well as reciprocate the piston body member. 60

2. A piston comprising a cylindrical piston body member, an end wall across one end thereof, a conical valve seat formed through said end wall with its enlarged diameter within the piston member, a piston rod, a pair of spaced baffle disks upon the piston rod within the body member, a valve member formed at the end of the piston rod and adapted to seat upon the conical seat in the end wall of the body member, and a ring 65 mounted in the open end of the body member to hold the baffle disks in the body member and allow said disks restricted movement as required to open and close the valve.

In testimony whereof I have signed my 75 name to this specification.

RUSSELL F. JOHNSON.
